(57) **CLAIM**

The ornamental design for a apron for retaining articles on a bucket, as shown.

DESCRIPTION

FIG. 1 is a perspective view of a apron for retaining articles on a bucket showing my new design;

FIG. 2 is a front elevation view;

FIG. 3 is a rear elevation view;

FIG. 4 is a right side elevation view;

FIG. 5 is a left side elevation view;

FIG. 6 is a top plan view; and,

FIG. 7 is a bottom plan view.

The broken lines showing in FIGS. 1 through 7 are for illustrative purposes only and form no part of the claimed design.

The cross-line pattern which is partially shown for ease of illustration, represents a conventional fabric and is understood to repeat uniformly throughout the indicated area.
